[57] **CLAIM**

The ornamental design for a hanger for table skirting, as shown and described.

DESCRIPTION

FIG. 1 is a top, front and right side perspective view of a hanger for table skirting showing my new design; FIG. 2 is a top, front and right side perspective view of a second embodiment thereof, with the view of the rear and side opposite being a mirror image, and with the bottom of this embodiment of the hanger being substantially flat, unadorned and of minimal thickness; FIG. 3 is a front elevational view thereof; FIG. 4 is a right side elevational view thereof; FIG. 5 is a top plan view thereof; FIG. 6 is a left side elevational view thereof; FIG. 7 is a rear elevational view thereof; and, FIG. 8 is a bottom plan view thereof.
